UNITED STATES PATENT OFFICE.

JAMES A. MORRISON, OF CLEVELAND, OHIO.

APPARATUS FOR OPERATING BELL VALVES.

Application filed November 10, 1924. Serial No. 749,110.

This invention is an apparatus for opening and closing the charging bells of blast furnaces and for operating bells whenever they are used for similar service.

One of the objects of the invention is to provide means for so controlling the operation of the charging bells that they may be gently opened and closed when desired, without jar or undesirable impact. A further object is to provide an apparatus of the character described, in which the power required for its operation is reduced to such an amount, as to be almost negligible, in fact, to such an extent that the operation will require during the opening of the bell, only sufficient power to overcome the normal friction of the mechanism and to actuate its parts, and during the closing movement sufficient power to raise the unbalanced part of the weight of the bell plus the friction of the machine. A further object is to provide a motor-operated apparatus for operating the bells of blast furnaces, so constructed that the opening and closing movements may be effected without reversing the direction of the actuating motor. A further object is to provide emergency means for stopping the apparatus when an undue resistance to movement is encountered, thereby preventing breakage due to closing the bells on pieces of the stock being charged into the furnace.

The invention will be hereinafter fully set forth and particularly pointed out in the claims.

In the accompanying drawing:

Figure 1 is a vertical cross section and elevation of a blast furnace bell-operating apparatus constructed in accordance with the invention. Figure 2 is an enlarged side elevation illustrating the operating mechanism. Figure 3 is a top plan view of the mechanism illustrated in Figure 2. Figure 4 is a detail view illustrating the brake mechanism. Figure 5 is a side elevation illustrating a modification of the cable connection between the drive gear and the bell lever. Figures 6 and 7 are vertical and horizontal sectional views, respectively, of the spring barrel illustrated in Figure 5. Figures 8 and 9 are diagrams illustrating the wiring of two different forms of apparatus controlling the operation of the motor. Figures 10, 11 and 12 are diagrammatic views illustrating the cycles of operation in

lowering and raising the bell. Figure 13 is a side view partly in section illustrating a modified form of limit switch. Figure 14 is a sectional view taken at right angles to Figure 13.

Referring to the drawings, 10 designates a portion of a blast furnace (conventionally illustrated), 11 the hopper, and 12 the bell which normally closes the bottom of the hopper 11. It is to be understood that the element 12 may be either the upper or lower bell of a blast furnace, because the invention is equally applicable to both.

The bell 12 is supported by a rod 13, which is attached by means of a flexible connection 14, to one end of a bell-beam 15, pivotally supported by suitable bearings 16. The other end of said bell-beam is provided with a counterweight 17 for counter-balancing a part of the weight of the bell 12.

Referring to Figures 1 and 2 of the drawings, 20 designates an electric motor, preferably of the shunt wound compound type, having a drive shaft 21, provided with a worm 22, meshing with and driving a worm wheel 23, on a counter shaft 24. Secured to said shaft 24 is a gear 25, meshing with the drive gear 26, which is keyed or otherwise secured to a gear shaft 27 mounted in suitable bearings 28.

Loosely mounted on the gear shaft 27 are two levers 30, one on each side of the gear 26, the outer or free ends of said levers being connected by a pin or bolt 31, which extends transversely through said wheel. Secured to the ends of the pin 31 are rope thimbles 32, to which are attached ropes 33, connected with an equalizer 34, normally located in a plane above the top of the gear 26. A cable 36 connects the equalizer 34 with the bell lever 15. The pivoted ends of the levers 30 are provided with grooves 37, to receive the ropes 33 during certain portions of the rotation of the drive gear 26.

A spring barrel or trunnion 40 is fulcrumed between the levers 30. Said barrel serves as a housing for a helical spring 41, which encircles a rod 42 passed longitudinally through the sleeve, and having its ends suitably anchored to spokes or other rigid portions of the drive gear 26. The rod 42 is provided with shoulders contiguous to its ends, forming stops for abutment washers 43, against which the ends of the spring react.

Any desired type of brake may be employed, a well-known braking mechanism being illustrated in Figure 4. Referring to said figure, the extension 45 of the motor shaft is provided with a brake disk 46, disposed between pivoted levers 47, 47^a, each of which is provided with a brake shoe 48, positioned to engage the disk. The lever 47 is connected by a link 49 with a pivoted field member 50, provided with a magnet coil 51. The free end 52 of the lever 47 is shaped to serve as an armature for said coil, and is normally engaged by a spring 53. In practice, the wiring of the magnet is connected directly across the line in parallel relation with the motor so that when the motor is in operation the current will be going through the magnet coil and will hold the armature up, pressing the spring 53 and releasing the brake shoes 48 from the brake disk 46. Whenever the current is shut off the motor, the magnet releases the armature, the spring 53 pushes the lever 47^a and its brake shoe over against the wheel, and exerts a pull on the lever 47 so as to bring its shoe against the other side of the wheel, stopping the wheel quickly and holding it in that position until the current is again turned on the motor and the brake released. The circuit to the motor is controlled by an automatic drum switch 54, so geared to the mechanism that when the circuit to the motor is closed through the medium of a suitable controller, said motor will revolve the gear 26 from the position of Figure 10, in the proper direction to relieve the pull upon the cable 36, until the pin or bolt 31 and the spring barrel 40 have moved through an arc of about 180°. By this time the bell 12 will have dropped to its lowermost position, so that the stock may fall off into the furnace (see Figure 11). The motor, however, continues to operate and drive the gear 26 in the same direction, until the pin or bolt 31 and spring barrel 40 have moved through a further arc of about 180°, or an arc equal to about one complete revolution of the drive gear 26 from the time its movement was first initiated, at which time the bell will again have reached its fully closed position (see Figure 12), whereupon the switch 54 will operate to shut off the current, stop the motor and set the brake. At the same time said switch reverses the field of the motor so that when the circuit is again closed the motor and the drive gear 26 will be driven in the opposite direction, and the operation repeated. It will be noted that as the drive gear rotates the levers 30 are moved on their fulcrum through the spring connection between their ends and the drive gear. The drum switch 54 may be of any desired type and said switch is therefore illustrated conventionally in Figures 2 and 3. In Figure 8 is illustrated the wiring diagram

for what may be termed a "torque limit relay switch," which possesses certain advantages. Referring to said Figure 8, the controller A, the controller panel B on which are mounted the panel switch D, the master switches C, C', the accelerating switch E, and the torque limit relay F, are located in the operator's house. The motor and drum switch 54 are mounted on the hoist.

Assuming that the panel switch D has been first moved to close the circuits through the line wires, when it is desired to operate the bell, the master controller A is thrown to either position, for instance, to the right as shown in Figure 8. The circuit then follows the line wire a⁴; contact a², panel switch D, wire a³, controller arm a from contact a¹ to contact a², and thence by one of the wires of cable X, to the wires a⁶ of the drum limit switch. From the limit switch the current passes by a second wire of cable X to the wire e and contact e'. From the last mentioned contact the current passes to wire a⁸, and via wire e² through the relay of contactor C, and by way of wire e³, switches e⁴ and e¹², return wire e⁵ and panel switch D, to the return line wire e⁶. At the same time current passes from the wire a⁸ through the relay of contactor C' and by wire e⁷ to switch e⁴, return wire e⁵, panel switch D to the line wire e⁶. The contactors C and C' are thereby actuated to close the circuits at contacts s, s and t, t, respectively, whereupon the current passes from the wire a⁸ through the relay of the accelerating switch E, wire e⁸, switch e⁹, contacts t, t, wire e¹⁰, contacts s, s, wire e¹¹, switch e¹², and return wire e⁵. Current also passes from the wire a⁸ through the energizing coil of the brake G, thence by wire e¹³ to contacts t, t, wire e¹⁰ contacts s, s, and to the return wire e⁵ over the same course as the circuit from the accelerating switch after leaving this point.

Passage of current through the relays of contactors C and C' brings the contacts of circuit closers h and h' into engagement, and current passing through the coil of brake G brings the contacts of circuit closers i and i' into engagement.

The motor starting circuit comprises the incoming line wire a⁴, panel switch D, wire k, coil k⁷ of the torque limit relay F, wire k² circuit closer i, wire k³, coil k⁴, wire k⁵, circuit closer i', wire k⁶, coil k⁷, wire k⁸, panel switch D, and return line wire e⁵.

From the motor starting circuit the main feeding circuits to the motor are as follows:

(1) From wire k², via circuit closer h, wire h³, shunt field h⁴ of the motor, wire h⁵, contacts h⁶, wire h⁷, contact h⁸, wire h⁹, contact h¹⁰, wire h¹¹, circuit closer h', wire h⁶, and thence over the course followed by the starting circuit from this point.

(2) A secondary circuit from the return

wire e^5 , by way of wire m , coil m' of the torque limit relay F, wire m^2 to the contact m^3 . At the last mentioned contact the current divides, part of it following the wire m^4 which is included among the wires in cable X, and passing into the main circuit via contact f' , controller arm a , and contact a^2 . The other branch of the circuit from contact m^3 follows wire m^5 , passing through the coil 10 m^6 to the return wire e^6 .

In Figure 9 the torque limit relay F is omitted, and hence the wire k is connected directly to the wire k^2 , the motor starting circuit being the same as described in connection with Figure 8, except for this slight 15 change. The secondary branch of the main feeding circuit in Figure 9 passes from switch e^{12} , through coil o' , and wire o^2 to the contact f' through cable X.

20 The torque limit relay F is provided with a series coil k' , through which all of the current used by the motor flows. The relay may be adjusted to operate at any desired current in excess of the full load motor current. If then, there is an obstruction to the closing of the bell, or should the drum switch fail to function, the load on the motor will build up as the spring 41 is compressed. When the load has built up to the 25 value for which the relay is set, the contacts with the said relay will be pulled open, and the control circuit for the switches C, C', and G will be broken, thus disconnecting the motor from the line and applying the brake.

From the foregoing it will be observed 30 that the torque limit relay is provided with a shunt holding coil m' which is energized whenever the master controller A is in operating position. The contacts of the torque limit relay will, therefore, be held open and the motor will be disconnected from the line until the torque limit relay is reset. This is accomplished by bringing the master controller to the off position. Then by reversing the master controller, the bell may be lowered in order to clear the obstruction.

In lieu of employing the spring barrel 40 and its method of spring connection between the levers 30, and the drive gear 26, the construction illustrated in Figures 6 and 7 may be employed. Referring to said figures, one end of the ropes 33 instead of being connected to the equalizer 34, which is in turn connected with the bell lever 15, is connected to a spring barrel S, the other end being connected through a rope thimble to a rigid pin in the gear.

Referring to Figures 6 and 7, 60 designates an abutment plate provided with a central tubular extension 61, through which is passed a rod 62, forming one member of a turnbuckle 63, the other member of which 65 is connected to the cable leading to the bell

lever 15. Said rod 62 is held in place by means of a nut 64, which is locked by means of a plate 65. Interposed between the plate 60 and an abutment plate 66 loosely mounted on the rod 62, are springs 67, retained in place by suitable rods 68, two of said rods being provided with eyes 69 by means of which the ropes 33 may be connected in place.

Carried by the spring barrel S is a casing 70, in which is located an automatic switch 71, conventionally illustrated, to which the circuit wires lead, as shown. The operation is practically the same as the construction illustrated in Figures 1, 2 and 3, i. e. any sustained resistance to movement of the bell will cause a compression of the springs 67 until the switch 71 is operated.

When the automatic switch 71 is carried by the spring barrel S, or when such a switch is carried by the gear 26, as indicated at 72, and operated through an arm 73 connected with the levers 30, as illustrated in Figure 13, the circuits are controlled by the switch in the manner illustrated in Figure 9. Referring to said figure, the circuits are identical with those illustrated in Figure 8, except that the torque limit relay F and its circuits and adjuncts are omitted. In this case, the normal control is through the contact elements of the drum switch 54, which break the motor circuit as the gear approaches a predetermined position, and the spring of the barrel S, or that carried by the barrel 40, (Figure 13), at the same time 100 is compressed a predetermined distance. In operation, should an obstruction become lodged between the bell and its seat while the bell is being raised, or should the drum switch 54 fail to function, and the spring 105 becomes compressed beyond a predetermined amount, the switch 70 or 72, as the case may be, will be thrown out, the circuit to the motor will be broken, and the brake set on the motor.

It will be readily apparent to those skilled in the art, that the motor is started but once, and runs continuously in one direction until the cycle is completed and the bell has been lowered, reversed and closed; that the closing can be made as gentle as is desired, by proper provision of slowdown contacts with drum switch 54; that if said switch fails to operate and shut off the motor when the bell is closed, the torque limit relay F, the switch 71, or the switch 72, as the case may be, will shut off the motor and set the brake, without any possible damage to the apparatus. Or if any piece of stock should 115 stick between the bell and the hopper, preventing the closing of the bell, the motor 120 will be stopped, the brake set, and damage entirely prevented.

It will also be readily understood that 125 when the bell is being lowered, the stock on 130

the bell will tend to overhaul the motor, and if the gearing is sufficiently efficient, it will make the motor run faster than its normal speed. In this case, because a shunt-wound or compound-wound motor is used, as soon as the motor has passed its normal speed, it becomes a generator and as such is a most effective brake, holding back on the rope, and preventing too rapid lowering of the bell.

10 The operation of the equipment is as follows:—

Starting with the bell closed, the current off the motor; the brake set; and a charge 15 of material in the hopper and resting on the large bell,—the current is turned on the motor; this also releases the brake. The torque of the motor, aided by the pull on the rope from the weight of the material on the 20 bell, starts and accelerates the motor rapidly until it has reached its normal speed. If the gearing is sufficiently efficient, the motor will pass its normal speed, and will immediately begin to generate current which will be 25 thrown back into the line, and at the same time the motor will hold back on the movement of the bell preventing its reaching a speed faster than is safe or desirable.

As the pin 31 carried by levers 30 approaches and passes the dead center, the bell is gradually slowed down, stopped and then raised. As the bell approaches its closed position, the automatic control gently slows down the motor and stops it when the bell 25 is actually closed, and sufficient tension has been applied on the rope to hold the bell shut when the stock is placed thereon, sets the brake and holds it there until the cycle is reversed and the operation repeated.

46 In case some material finds lodgment between the bell and the edge of the hopper, preventing the mechanism from completing the cycle as just described, the motor, of course, continues to revolve, thereby causing 50 the levers 30 to compress the spring 41 until sufficient torque is generated to operate the torque limit relay F, causing the current to be cut off from the motor and the setting of the brake. Or if an automatic switch is employed in lieu of the torque limit relay, the same result is secured through the operation of said switch. In either form of apparatus the equipment is protected from 55 damage.

55 In case the drum switch 54 should fail to operate and stop the mechanism, when the bell has reached its closed position and can not travel any farther, then the motor will be stopped by the torque limit relay or the 60 automatic switch, as the case may be, and held in position until repairs or adjustment can be made to the drum switch, so that it will operate satisfactorily.

65 It will be readily understood that this equipment requires a minimum expenditure

of power in its operation. In fact, if the gearing is sufficiently efficient it becomes to some extent a power generator instead of a power user during the lowering of the bell. In its safety features it is absolutely effective, because any failure of the control mechanism or fouling of the parts, will immediately result in the stopping of the motor and the setting of the brake, without introducing into any part of the equipment any strain greater than that required to compress the spring so that the motor will be stopped through the operation of the torque limit relay or the automatic switch which of course, is only slightly in excess of the usual operating strains.

70 It is to be understood that while the invention has been illustrated and described in connection with the operation of bells for blast furnaces, it is not limited to this particular art, but is equally applicable to any kind of bell valve, whether a blast furnace bell, or for shutting off the flow of gas in other connections, or for any similar use of a bell for closing an aperture.

75 Having thus explained the nature of the invention and described an operative manner of constructing and using the same, although without attempting to set forth all of the forms in which it may be made, or all 80 of the forms of its use, what is claimed is:—

85 1. An apparatus for operating bell valves comprising bell-operating means including a cable, a motor-driven hoist member, and means yieldably connecting said hoist member and one end of said cable.

90 2. An apparatus for operating bell valves comprising a bell-operating lever, a motor-driven hoist member, an operating cable positively connected at one end to said lever, and means yieldably connecting the other 100 end of said cable to said hoist member.

95 3. An apparatus for operating bell valves comprising a bell-operating lever, a motor-driven hoist member, ropes extending to positions on opposite sides of said hoist member, an operating cable connected at one end to said lever and at the other end to both of 110 said ropes, and a yieldable device connecting said ropes and said hoist member.

115 4. An apparatus for operating bell valves comprising a bell-operating lever a motor-driven hoist member, an operating cable positively connected at one end to said lever, and means yieldably connecting the other 120 end of said cable to said hoist member at a position normally fixed with relation thereto.

125 5. An apparatus for operating bell valves comprising bell-operating means including a cable, a motor-driven hoist member, means yieldably connecting said hoist member and one end of said cable, and means for limiting the revolutions or travel of the hoist member.

6. An apparatus for operating bell valves comprising a bell-operating lever, a reversibly operated motor-driven hoist member, arms pivoted at one end on the axle or shaft of said hoist member and having their other ends connected to said member, ropes connected to the free ends of said arms, and means connecting said ropes to said bell-operating lever, said arms having cable receiving grooves at their pivoted ends. 70

7. An apparatus for operating bell valves comprising bell-operating means including a cable, a reversibly operable motor-driven hoist member, arms each pivoted at one end on the axis of said hoist member, a yieldable connection between the free ends of said arms and said hoist member, and connections between said arms and said cable. 15

8. An apparatus for operating bell valves comprising bell-operating means including a cable, a reversibly operable motor-driven shaft, a hoist member rotatable with said shaft, an arm pivoted at one end to said shaft and yieldably connected at its free end to said hoist member, and means connecting said arm and said cable. 25

9. An apparatus for operating bell valves comprising bell-operating means including a cable, a reversibly operable motor-driven hoist member, arms each pivoted at one end on fulcra coinciding with the axis of said hoist member, a pin connecting the free ends of said arms, means yieldably connecting said pin with said hoist member, and means connecting said arms with said cable. 35

10. An apparatus for operating bell valves comprising bell-operating means including a cable, a reversibly operable motor-driven hoist member, arms each pivoted at one end on fulcra coinciding with the axis of said hoist member, a spring barrel mounted between the free ends of said arms, a spring mounted in said barrel and reacting against fixed portions of the hoist member, and means connecting said arms with said cable. 45

11. An apparatus for operating bell valves comprising bell-operating means including a cable, a reversibly operable motor-driven hoist member, arms each pivoted at one end on fulcra coinciding with the axis of said hoist member, a pin connecting the free ends of said arms, a spring barrel pivotally mounted on said arms, anchoring means for said barrel, a spring located in said barrel and reacting against fixed abutments, and means connecting the free ends of said arm with said cable. 50

12. An apparatus for operating bell valves comprising bell-operating means including a cable, a reversibly operable motor-driven hoist member, arms each pivoted at one end on fulcra coinciding with the axis of said hoist member, a pin connecting the free ends of said arms, a spring barrel pivotally mounted on said arms, a rod extended

through said barrel and secured to said hoist member, a spring encircling said rod, abutments carried by said rod against which said spring reacts, and means connecting the free ends of said arms with said cable. 70

13. An apparatus for operating bell valves comprising bell-operating means including a cable, reversibly operable motor-driven hoist member arms each pivoted at one end on fulcra coinciding with the axis of said hoist member and having cable receiving grooves at their pivoted ends, means connecting the free ends of said arms to a normally fixed position on said hoist member, ropes connected to the free ends of said arms 80 and positioned to enter said grooves, and means connecting said ropes with said cable. 75

14. An apparatus for operating bell valves comprising bell-operating means including a cable, a reversibly operable motor-driven hoist member, arms each pivoted at one end on fulcra coinciding with the axis of said hoist member and having cable receiving grooves at their pivoted ends, means connecting the free ends of said levers to a normally fixed position on said hoist member, ropes connected to the free ends of said levers and positioned to enter said grooves, and a cross-head connecting said cable and said ropes. 95

15. An apparatus for operating bell valves comprising bell-operating means including a cable, a motor-driven hoist member, means yieldably connecting said hoist member and one end of said cable, and emergency means controlled by said yieldable connection for shutting off the motor. 100

16. An apparatus for operating bell valves comprising bell-operating means, a reversibly operable motor-driven hoist member, levers each pivoted at one end on fulcra coinciding with the axis of said hoist member, means yieldably connecting the free ends of said levers and said hoist member, connections between said lever and said bell-operating means, and emergency means controlled by said yieldable connection for shutting off the motor. 110

17. An apparatus for operating bell valves comprising bell-operating means, a reversibly operable motor-driven hoist member, levers pivoted at one end on fulcra coinciding with the axis of said hoist member, a spring barrel mounted between the free ends of said levers, a spring mounted in said barrel and reacting against fixed portions of the hoist member, means connecting said levers with said bell-operating means, and emergency means controlled by said spring for shutting off the motor. 115

18. A bell hoisting member comprising bell operating means, a motor, a hoisting gear operated thereby, means yieldably connecting said gear and said bell operating means, and a torque limit relay controlling 130 120 125

the motor circuit and operable through the torque developed by said yieldable connection.

19. A bell operating apparatus comprising bell-moving means, a motor, a hoist member operated thereby, a yieldable connection between said hoist member and said bell-operating means, a drum limit switch controlling the operation of the motor, and a torque limit relay operable to stop the motor when the drum switch fails.

20. A bell operating apparatus comprising bell-moving means, a motor, a hoist member operated thereby, means yieldably connecting said hoist member and said bell-operating means, and a torque limit switch having a series coil in the motor circuit, said switch being set for a predetermined torque value to be developed by said yieldable connection.

21. A bell operating apparatus comprising bell-moving means, a motor, a hoist member operated thereby, a yieldable connection between said hoist member and said bell moving means, a drum limit switch controlling the operation of the motor, and a torque limit switch having a series coil in

the motor circuit, said torque limit switch being set for a predetermined torque value to be developed by the yieldable connection. 30

22. A bell operating apparatus comprising bell-moving means, a motor, a hoist member operated thereby, a yieldable connection between said hoist member and said bell operating means, and a torque limit switch having a series coil in the motor circuit, said switch being set for a predetermined torque value to be developed by said yieldable connection, said torque limit switch also having a shunt holding coil 40 operable when the drum switch fails.

23. A bell hoisting apparatus comprising bell-operating means including a cable, a motor, a hoisting member operated thereby, a yieldable connection between said hoisting member and said cable, a torque limit relay controlling the motor circuit and operable through the torque to be developed by said yieldable connection, and means whereby the torque limit switch may be reset by reversing the motor controller. 45

In testimony whereof I have hereunto set my hand.

JAMES A. MORRISON.
